WOVEN FABRIC CONVEYER AND LIKE BAND

Cecil Edward Gyatt, North Harrow, England,
assignor to Eastman Kodak Company, Rochester, N. Y., a corporation of New York

Application January 26, 1934, Serial No. 708,437
In Great Britain February 7, 1933

2 Claims. (Cl. 198—193)

This invention relates to woven fabric conveyer and like bands such as are used for various purposes, and in particular to those employed for conveying photographic prints and the like over a series of rollers in the course of which the prints are dried.

Experience has proved that it is desirable to employ a full-bodied fabric usually of a twill weave with closely packed weft threads if a satisfactory drying surface is to be provided, but as in practice such conveyers are apt to move laterally relatively to the rollers over which they pass, it is found that the edges or selvedges of the band tend to wear out even if the width of the band exceeds the length of the rollers. Excessive lateral movement of the band as it passes over the rollers is prevented if a rope or cord is secured to each edge of the band, but if the edges are merely made to enclose the rope the fabric tends to pucker or cockle to such an extent that when the reinforced edge passes over small diameter rollers the edges of the band wear out even sooner than when they are not reinforced. The present invention has for its object to overcome this difficulty.

To this end a conveyer or like band according to the present invention comprises a woven fabric band having a rope or cord secured to each selvedge of the band by being enclosed in a length of fabric in which the warp and weft threads are so arranged that there is no puckering of the fabric which surrounds the rope even when the latter is bent, as in passing over a roller of small diameter. The rope or cord may be secured to each selvedge of the band by a separately formed woven strip which encloses the rope and is attached to the band at or near the selvedge. Thus, when the rope is bent, as in passing round a roller of small diameter, there is no appreciable buckling of the fabric surrounding the rope.

The fabric surrounding the rope may be arranged with its warp and weft threads inclined to the length of the rope, the fabric being preferably cut on the bias. Alternatively each rope may be enclosed in a series of separately formed pieces of fabric each of which encloses the rope and is arranged with its warp threads approximately at right angles to the length of the rope, a gap or clearance being preferably left between successive pieces of the enclosing fabric.

In the accompanying drawings,

Figure 1 illustrates in plan a short length of a conveyer band embodying one form of the invention.

Figure 2 illustrates on an enlarged scale a part of one selvedge of the band shown in Figure 1.

Figure 3 is a section, also on an enlarged scale, on the line III—III of Figure 1.

Figure 4 illustrates in a manner similar to that of Figure 2, an alternative form also according to the invention, and

Figure 5 illustrates in plan yet another form of band also embodying the invention.

In the construction illustrated in Figures 1, 2 10 and 3 the woven fabric band A constituting the body of the conveyer band is furnished at each selvedge with a reinforcing rope or cord B. Each rope B is enclosed in a strip of twill tape B¹ which is folded over so as to embrace the rope B and 15 the selvedge of the band A slipped between the two selvedges of the tape B² and united thereto by two rows of stitching as shown at B³.

As clearly shown in Figure 2 the warp threads C as also the weft threads C¹ are inclined to the 20 length of the rope B, these threads being, in the construction shown, inclined at an angle of approximately 45° to the length of the rope. When therefore the band A is passed over a roller of small diameter so that each rope B is bent on 25 a small radius the enclosing tape B¹ will not tend to pucker or cockle to any appreciable extent since the inclination of the warp and weft threads will allow these to close together evenly.

In the form illustrated in Figure 4 each of the 30 reinforcing ropes or cords D is enclosed in a series of short lengths of fabric—the warp threads E¹ of which are approximately at right angles to the length of the rope D. A small gap or clearance E² is then left between successive lengths of 35 the enclosing fabric. When a band constructed in this manner is passed over a roller of small diameter the gaps E² between each pair of adjacent lengths of the enclosing fabric allow the fabric to contract on the inside and thus tend to 40 reduce risk of the fabric buckling.

The band F illustrated in Figure 5 is furnished at each selvedge with a rope or cord G which is 45 enclosed by a marginal portion G¹ of the band F. The band is cut on the bias so that the warp and weft threads of the fabric G¹ enclosing each rope are inclined to the length of the rope.

It will therefore be seen that in a conveyer band embodying the present invention the fabric can 50 be curved round quite a small diameter roller without any cockling arising. As a result the edge of the band is satisfactorily reinforced, excessive lateral play is prevented, and there is no tendency for undue wear to take place such as 55

arises when the thread puckers or buckles as when passing over a small diameter roller.

Certain forms of tape can be satisfactorily used to enclose the rope which reinforces the edges of the band and in particular twill tape in which the twill effect is produced either wholly or partly by the warp threads.

It will be understood that the constructions above described are given by way of example only 10 and that details may be modified.

What I claim as my invention and desire to secure by Letters Patent is:—

1. In a conveyer band the combination with a woven fabric band, of a reinforced edge there-

for comprising a rope, means for joining the rope and band including a fabric strip having warp and weft threads angularly disposed with respect to said rope whereby relative movement between the band and rope may take place without puckering. 5

2. In a conveyer band the combination with a woven fabric band, of a reinforced edge therefor comprising a rope, means for joining the rope and band and for holding them in spaced relation including a fabric strip having both the warp and weft threads angularly disposed with respect to the rope whereby a resilient connection is formed. 10

CECIL EDWARD GYATT.
